METHOD AND APPARATUS FOR MAKING
AND DECANTING CHAMPAGNE

Willard C. Saville, Belvedere, Calif.

Application October 15, 1934, Serial No. 748,351

21 Claims. (Cl. 226—26)

This invention relates to a method for making champagne and an apparatus for decanting champagne fermented in bottles.

The primary object of the invention is to provide a method whereby champagne can be fermented in one bottle and then can be decanted into another bottle without losing any of the pressure or gas from the champagne; the steps of the method being such as to prevent the transfer of any sediment from the first to the second bottle.

Another object of the invention is to provide an apparatus whereby champagne can be decanted from a capped bottle directly into a clean bottle without the loss of any pressure or gas and without transferring any sediment.

Another object of the invention is to provide an apparatus wherein champagne fermented in one bottle can be decanted into another clean bottle by the use of a syphon which is adapted, if necessary, to pierce the closure or cap of the bottle in which the champagne was fermented; means being provided for conveniently receiving and gripping the bottles and for suitably moving the syphon and to open and close the syphon at the proper times and in the proper positions.

In this specification and the annexed drawings, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

This invention is clearly illustrated in the accompanying drawings, wherein

Figure 1 is a front view of the apparatus, part of the casing being shown broken away.

Figure 2 is a side view of the apparatus with part of the side of the casing shown broken away.

Figure 3 is a fragmental view of the apparatus showing the capped bottle in place in operative relation to the piercing end of the syphon.

Figure 4 is a fragmental view of the apparatus showing the clean bottle in place below the outlet end of the syphon.

Figure 5 is a front view of the holder for the bottom of the bottles.

Figure 6 is a side view of said bottle holder.

Figure 7 is a fragmental view of the syphon showing the arrangement of the filter therein.

Figure 8 is a fragmental view partly in section of the piercing side of the syphon.

Figure 9 is a fragmental rear view of the apparatus showing the pinion and rack arrange-

ment for the raising and lowering of the syphon, and

Figure 10 is a front view partly in section of the pressure control valve.

The common method heretofore used for clearing champagne fermented in bottles included the daily shaking and changing the inclination of the position of the bottle until the said bottle stood on its top and all sediment settled down upon its cork, then the cork was caused to suddenly escape from the bottle. The pressure in the bottle, in blowing out the cork, also ejected the dirt or sediment settled upon the cork. Then the neck of the bottle had to be wiped and cleaned before the bottle was recorked. Obviously there was a great deal of pressure lost in addition to loss of champagne during the performance of this old method.

The necessity for the above tedious disgorging operation is obviated by my method and process of making champagne.

In carrying out my invention the wine is placed in a bottle provided with suitable yeast and culture to carry on additional fermentation, then this bottle is capped preferably by the usual metal cap clamped over the rim of the bottle. The bottled wine is kept for a period necessary to complete fermentation. Usually the fermentation is completed within a month. Before decanting the bottle is shaken and then set either on its bottom or its top, depending on the arrangement of the apparatus used.

In the present illustration the apparatus is adopted for decanting wine where the sediment is collected on the bottom. The sediment collects on the bottom in about two days.

Then the bottle of wine is chilled to almost freezing point to help precipitation and hardening of the sediment. If necessary the end of the bottle where the sediment is collected may be placed on dry ice or other quick refrigerant to harden the sediment.

Then an end of a conduit, adapted to work substantially like a syphon, is extended into the bottle in such position that the intake end of the syphon is spaced from the accumulated sediment. Preferably this is accomplished by piercing the metal cap and extending the syphon to about one inch from the bottom of the bottle so as to leave the sediment at the bottom undisturbed. Where the sediment is collected at the cap in upside down position of the bottle the end of the syphon is extended through the cap and the hardened sediment to about an inch above the accumulated sediment. The other end of the syphon is ex-

tended into a clean bottle which latter is preferably also chilled nearly to freezing temperature. It is also preferable that the syphon itself be kept very cold.

5 Then the pressure is equalized between the empty and the full bottle so that the champagne is at all times under a pressure equal to or greater than the pressure developed in the course of fermentation. On account of the chilling the gases 10 are held in solution in the champagne and the champagne is not disturbed during its transfer either by air pockets or eddy currents.

The equalization of the pressure may be accomplished either by returning the air from the 15 clean bottle to the bottle from which the champagne is decanted as the latter empties; or gas, such as air, under pressure equal to or higher than the pressure of the champagne is introduced into the clean bottle and also into the full bottle. Then the syphon is opened and the bottle is 20 decanted so as to keep the pressure equal during decanting.

Lastly after the clean bottle is filled the same is corked.

25 It is to be noted that before the syphoning begins a suitable amount of liquor is placed in the clean bottle.

My apparatus for decanting champagne includes in its general organization a base 6 which 30 is adapted to be secured to a wall or other support 7 by any suitable means such as bolts 8 in such a way that the base 6 is spaced from the wall 7 for the purpose of accommodating certain moving parts to be hereinafter described. Near the 35 lower portion of the base 6 are mounted spring urged bottle holders 9 and 10. The bottle holders 9 and 10 may be at the same level or the holder 9 may be at a higher level than the holder 10. Above the holder 9 and aligned therewith is 40 a fixed sealer head 11. Above the holder 10 and aligned therewith is another fixed sealer head 12. The bottle 13 filled with fermented wine is gripped between the holder 9 and sealer head 11. A clean champagne bottle 14 containing a 45 determined amount of liquor, as indicated at 16 in Figure 4, is gripped between the holder 10 and sealer head 12. A U shaped conduit, hereinafter called syphon 17, has its curved bend 18 clamped in a bracket 19 which is supported on the base 6 with freedom of vertical movement. The intake side 21 of the syphon 17 is guided in and extends through the sealer head 11 while the outlet side 22 of the syphon 17 is guided in and extends through the sealer head 12. An adjusting mechanism denoted in its entirety by the numeral 23 is adapted to move the bracket 19 and the syphon 17 therewith, vertically so that the respective ends of the syphon are inserted into or taken out of the respective bottles 13 and 14 at will. Pressure means such as a tank 24 provides the gas or air under pressure to be distributed through a three way valve 26 and through the respective sealer heads 11 and 12 into the bottles 13 and 14.

60 In detail the construction of the holders 9 and 10 are identical and the description of one will suffice. A U shaped holder bracket 27 is mounted on the base 6 so that the flanges thereof extend away from said base. A shaft 28 is vertically 65 slidable through the flanges of the bracket 27. On the shaft 28 and below the upper flange of the bracket 27 is a collar 29. A strong coil spring 31, wound around the portion of the shaft 28 between the collar 29 and the lower flange of the bracket 27, exerts all its force for pushing the

collar 29 and the shaft 28 upwardly. On the top of the shaft 28 is a wooden tray 32 to provide a seat for the bottle 13 or 14 and hold the bottle in alignment with and against the respective sealer head 11 or 12.

5 In order to put the bottles in place the wooden tray 32 and the shaft 28 must be pulled downwardly against the action of the strong spring 31. For this purpose a yoke 33 is fulcrumed on a pin 34 substantially intermediate between the flanges of the bracket 27. The yoke terminates in a comparatively long lever 36 in order to provide leverage. This lever 36 may be operated by hand as on the holder 9 or as a foot pedal as on the holder 10. A link 37 is connected to each 15 side of the yoke 33 at a point between the pivot 34 and the lever 36. The links 37 extend downwardly along the opposite sides of the bracket 27 and to a point below the lower flange of said bracket 27. A cross head 38 is secured between 20 the lower ends of the links 37 and into this cross head is fixed the reduced lower end of the shaft 28. Thus when the lever 36 is pressed downwardly it moves the links 37 and the cross head 38 downwardly thereby moving the shaft 28, collar 29 and tray 32 against the action of the spring 31 so as to allow the placing of the bottle 13 or 14 on the top of the respective tray 32. When the lever 36 is released the bottle is pressed firmly 25 between the tray 32 and the respective sealer 30 head 11 or 12 by the action of the spring 31.

The sealer heads 11 and 12 are also substantially identical therefore the description of one will suffice. Each sealer head is supported on a ring bracket 39 which in turn has a flange 41 35 suitably secured to the base 6. A sealer casing 42 is extended through the ring 39 so that its externally threaded lower end projects below the ring 39 to be engaged by a hollow nut 43 so as to be held in place. It is to be noted that the sealer casing 42 is flanged and shouldered to rest upon the upper face of the ring 39. The sealer casing 42 is hollow so as to contain a suitable packing such as an apertured rubber packing 44 for engagement with the rim of the top or mouth of the bottle, for sealing the latter when pressed in place.

The sealer casing 42 has an upwardly extended tubular neck to slidably guide the respective end of the syphon. The upper end of a neck is suitably sealed by the usual packing gland 46. It is to be noted that the interior passage 47 of each sealer casing 42 has a side passage 48 extended thereinto in order to conduct air or gas into or from the sealer casing 42. The passage 48 in the sealer head 11 is connected by a tube 49 to an outlet port of the valve 26, while the passage 48 in the sealer head 12 is connected by a tube 51 to another outlet port of the valve 26. The inlet port of said valve is connected by a tube 52 60 to the pressure tank 24 in the usual way.

The inlet side 21 of the syphon 17 has a piercing plug 53 threaded in the end thereof and immediately above the plug 53 a plurality of inlet openings 54 are provided. These inlet openings 65 54 are normally covered by an external sliding sleeve 56 which latter is urged against the top of the plug 53 by a coil spring 57. The spring 57 is coiled around the tube 21 and bears against a packing nut 58 at its upper end and against the packing nut 59 on the top of the sleeve 56 so as to urge the sleeve 56 downwardly. It is to be noted that the piercing plug 53 is sharply pointed so as to pierce and press through the metal cap 61 on the bottle 13 and produce a hole therein 75

which is larger than the diameter of the siphon tube 21. Slightly below the upper end of the sliding sleeve 56 is an abutment shoulder 62 so spaced that it reaches the top of the packing gland 66 of the sealer head 11 before the piercing plug 53 would reach its lowermost position, so that upon further downward movement of the siphon 17 the sleeve 56 remains stationary while the end of the tube 21 is pushed out of the end 10 of the sleeve 56 thereby uncovering the inlet openings 54 at a point safely spaced above the accumulated sediment on the bottom of the bottle 13. At this point further downward movement of the siphon is prevented by an adjustable 15 stop 63 against which the bracket 19 abuts. The upward movement of the bracket 19 is limited by another adjustable stop 64 above the top of the bracket 19. When the siphon is moved upwardly and away from the sealer head 11 the action of 20 the spring 57 will promptly urge the sleeve 56 over the inlet openings 54 to keep the same closed.

The end of the outlet side 22 of the siphon 17 may be open, or if necessary an abutment valve of the type shown in Figure 4 may be used. For 25 this purpose the end of the outlet siphon tube 22 is provided with a reduced passage 66 terminated at its upper end in a valve seat 67. A valve stem 68 of star cross section is slideable in the passage 66 and carries on its upper end a valve 69 of 30 smaller diameter than the inner diameter of the siphon tube 22. The outlet siphon tube 22 is of such length that when the inlet openings 54 are uncovered in bottle 13 at the same time the valve stem 68 is so engaged with the bottom of the bottle 14 that it raises the valve 69 off the seat 67. The valve 69 is urged back to closed position by a spring 70. The ends of the siphon 17 in the uppermost position remain in the respective sealer heads 11 and 12, but clear of the mouths of 40 the respective bottles 13 and 14.

At the top of the outlet side 22 of the siphon 17 a filter is provided, the filter consists of a sterilized felt disk 71 secured across the siphon passage in any suitable manner such as between flanges 72 45 by a nut 73. This filter prevents the passing of germs or impurities in the course of decanting.

The siphon 17 is moved vertically by moving the bracket 19 along the face of the base 6. This movement may be accurately controlled hydraulically or electrically or by any other suitable mechanism. For purposes of illustration the adjusting mechanism 23 is connected to the rear of the bracket 19. The bracket 19 is provided with a tongue 74 which extends rearwardly 50 through and is slideable in an elongated vertical slot 76 in the base 6. To this tongue 74 is fixedly secured a rack 77 disposed along the rear face of the base 6. Said rack 77 is wider than the slot 76 so as to hold the bracket 19 in place on the base 6. The teeth of the rack 77 are engaged by a pinion 78 which latter is on a pinion shaft 79 extending forwardly through the base 6. A hand wheel 81 is provided in the front end of the shaft 79 whereby the shaft 79 and the pinion 78 60 can be turned and the rack 77, bracket 19 and siphon 17 can be lowered or raised at will.

The three way cock valve 26 is illustrated in detail in Figure 10. When the handle 82 of this cock valve 26 is turned to the right viewing Figures 1 and 10, thus the pressure tank 24 is connected through the conduit 52 to conduit 51 and to the sealer head 12, then the bottle 14 is filled with the desired pressure medium. By turning the handle 82 in a contraclockwise direction, 70 viewing Figures 1 and 10, the pressure tank 24

is connected to conduit 49 to admit the pressure medium into the sealer head 11 and into the space above the champagne in the bottle 13. This pressure is applied in bottle 13 until the bottle 13 is emptied to the inlet openings 54 of the 5 siphon 17. In this manner pressure is equalized in the whole apparatus. Increasing pressure in the bottle 14 as the same is being filled with champagne will cause the opening of an escape- 10 ment valve 83 connected to the conduit 51 near the sealer head 12. For continuous supply of pressure medium such as compressed air the pressure tank 24 is connected in the usual way by a pipe 84 to a compressor, not shown.

To render the operation of the machine still 15 more efficient the entire apparatus above the sealer heads 11 and 12 is covered by a casing 86 which is made of heat insulating material. The enclosure within the casing 86 is kept at nearly freezing temperature by any suitable refrigerant. 20 As an illustration I show the usual refrigerating coils 87 in which a refrigerant is circulated in any usual manner. The pressure tank 24 is also placed into a container 88 which is provided with any suitable refrigerant such as ice 89, to keep 25 the pressure medium also at a very cold temperature. As heretofore stated both the full bottle 13 and the empty, clean bottle 14 are chilled to nearly freezing temperature. Thus the gases in the champagne are kept in solution through- 30 out the entire decanting operation.

In operation first the chilled, full bottle 13 is placed into the holder 10 and pressed against the sealer head 11, without removing the metal cap 61. Then the clean bottle 14 chilled with the 35 required amount of liquor in it is placed within the holder 10 and sealer head 12.

Then the hand wheel 81 is turned so as to lower the siphon 17 and pierce the cap 61. When the abutment shoulder 62 of the sleeve 56 reaches 40 the top of the sealer head 11 the lowering is stopped momentarily before the inlet openings 54 are uncovered.

Then compressed air of the same or higher pressure than the pressure in the fermented wine 45 is introduced into the bottle 14. Thereafter the valve handle 82 is so turned as to introduce the same pressure above the champagne in bottle 13, and it is left in this open position. Then the siphon 17 is lowered to its lower limit uncovering 50 the inlet openings 54 and at the same time the stem 68 strikes the bottom of the bottle 14 and raises the valve 69 off its seat 67 to allow the flow of champagne out of the siphon 17. The champagne thus flows out of the bottle 13 through the 55 inlet openings 54, the siphon 17 and out through the passage 66 into the bottle 14. As the bottle 14 is being so filled under equalized pressure the rising level of the champagne forces the compressed air out through the escapement valve 83. 60 After the bottle 14 is filled the valve 82 is turned to shut off the pressure supply. Then the siphon 17 is raised out of the bottles automatically closing the inlet and outlet valve of the siphon. The bottles are then removed from the apparatus. 65 Then the bottle 14 is corked in the usual manner but without loss of gas or pressure because the same are still in solution on account of the continuous chilling throughout the entire operation. The siphon 17 is left filled with chilled cham- 70 pagne, held therein by the closed inlet and outlet of the siphon 17, and is thus ready for decanting another bottle.

The method and apparatus heretofore described is also applicable when the empty bottle 75

14 is so much smaller than the full bottle 13 that several empty bottles 14 may be filled from one full bottle 13. For instance from a full quart bottle, four splits may be filled successively, but 5 by the same principle of operation.

Having thus described my invention what I claim and desire to secure by Letters Patent is:

1. In an apparatus for transferring champagne from a bottle in which it was fermented into 10 another bottle, the combination with means for holding each bottle stationary, and a closure member for each bottle adapted to engage the mouths of said bottles of a syphon, means to simultaneously insert the ends of the syphon 15 through said closure members into the respective bottles so as to cause the flow of champagne from the full to the empty bottle, and means for the gradual escapement of air from the second bottle as it is being filled.
- 20 2. In an apparatus for transferring champagne from a bottle in which it was fermented into another bottle, the combination with means for holding each bottle stationary, and sealer means for each bottle adapted to engage the mouth of 25 said bottle, of a syphon, means to simultaneously insert the ends of the syphon into the respective bottles so as to cause the flow of champagne from the full to the empty bottle, means for the gradual escapement of air from the second bottle as 30 it is being filled, and means to keep the sealer means and said syphon at low temperatures.
3. In an apparatus for transferring champagne from a bottle in which it was fermented into another bottle, the combination with means for 35 holding each bottle stationary, including an element at the mouth of the bottle of a syphon, means to simultaneously insert the ends of the syphon through said element and into the respective bottles so as to cause the flow of champagne 40 from the full to the empty bottle, means for the gradual escapement of air from the second bottle as it is being filled, and means on the side of the syphon adjacent the full bottle to keep said syphon closed until the inlet end of the syphon 45 reaches a predetermined position in the full bottle.
4. In an apparatus for transferring champagne from a bottle in which it was fermented into another bottle, the combination with means for 50 holding each bottle stationary, including an element at the mouth of the bottle of a syphon, means to simultaneously insert the ends of the syphon through said elements and into the respective bottles so as to cause the flow of champagne 55 from the full to the empty bottle, and means for the gradual escapement of air from the second bottle as it is being filled, and means at both ends of the syphon to keep said syphon closed until it reaches a predetermined position 60 relatively to said bottles.
5. In an apparatus for transferring champagne from a closed bottle in which the champagne was fermented into another bottle, and means to hold each bottle in place and sealed, of a conduit 65 adapted to conduct fluid from the full bottle to the empty bottle, and being adapted to have its ends introduced into the respective bottles through said sealing means, means to move said conduit into and out of said bottles at will, a member on the inlet end of the conduit adapted to penetrate through the closure of the full bottle as the conduit ends are introduced into said bottles, and means to prevent the flow through 70 said conduit until the inlet end of the conduit

reaches a predetermined position in the full bottle.

6. In an apparatus for transferring champagne from a closed bottle in which the champagne was fermented into another bottle, and means to hold 5 each bottle in place and sealed, of a conduit adapted to conduct fluid from the full bottle to the empty bottle, and being adapted to have its ends introduced into the respective bottles through said sealing means, means to move said conduit into and out of said bottles at will, a member on the inlet end of the conduit adapted to penetrate through the closure of the full bottle as the conduit ends are introduced into said bottles, and means to prevent the flow through 10 said conduit until the inlet end of the conduit reaches a predetermined position in the full bottle, said member being adapted to open an aperture in the closure larger than the diameter of the inlet side of the conduit.

7. In an apparatus for transferring champagne from a closed bottle in which it is fermented into another bottle, means for holding the bottles in position and for sealing the mouths of the bottles from the atmosphere, a syphon having 15 its ends extended into and guided in said sealing means into and out of said bottles, means for moving said syphon toward and away from said bottles, means to introduce a cold, aeriform, pressure medium selectively into said bottles, and 20 means to automatically control the opening of the inlet end of the syphon in accordance with the position of the syphon relatively to said bottles.

8. In an apparatus for transferring champagne from one bottle to another bottle, the combination 35 with means for holding said bottles in place, sealing means for the mouths of said bottles, and adjustable syphoning means to syphon the champagne from the full to the empty bottle, of means to keep the bottles, the sealing means, and 40 the syphoning means at substantially uniform temperature so as to keep the champagne at a near freezing temperature throughout the entire transfer, and means to equalize the pressure through the bottles and said syphon.

9. In an apparatus for transferring effervescent liquid from one bottle to another, means to seal the mouths of the bottles, means to hold the bottles in engagement with the sealing means, adjustable means to establish communication between the bottles through said sealing means so 50 as to allow the flow of the effervescent liquid from the full to the empty bottle.

10. In an apparatus for transferring effervescent liquid from one bottle to another, means to seal the mouths of the bottles, means to hold the bottles in engagement with the sealing means, adjustable means to establish communication between the bottles through said sealing means so as to allow the flow of the effervescent liquid from 55 the full to the empty bottle, the full bottle having a closure thereon, and an element on said means of communication to penetrate said closure so as to permit flow of liquid from said bottle into said means of communication.

11. In an apparatus for transferring effervescent liquid from one bottle to another, means to seal the mouths of the bottles, means to hold the bottles in engagement with the sealing means, adjustable means to establish communication between the bottles through said sealing means so as to allow the flow of the effervescent liquid from the full to the empty bottle, and pressure means to create and maintain pressure in said bottles.

12. In an apparatus for transferring efferves-

cent liquid from one bottle to another, means to seal the mouths of the bottles, means to hold the bottles in engagement with the sealing means, adjustable means to establish communication between the bottles through said sealing means so as to allow the flow of the effervescent liquid from the full to the empty bottle, pressure means to create and maintain pressure in said bottles, and refrigeration means for all the parts of the apparatus that contact with said liquid.

13. In an apparatus for transferring effervescent liquid from a full bottle to an empty bottle, means to hold a full bottle, and an empty bottle, including a sealing head, means movable relatively to said sealing head to establish communication between said bottles, a filter interconnected in said means of communication, and pressure means to create and maintain constant pressure so as to cause the content of the full bottle to flow into the empty bottle.

14. In an apparatus for transferring effervescent liquid from a full bottle to an empty bottle, means to hold a full bottle, and an empty bottle, including a sealing head, means movable relatively to said sealing head to establish communication between said bottles, a filter interconnected in said means of communication, and pressure means to create and maintain constant pressure so as to cause the content of the full bottle to flow into the empty bottle, and means of escape-
ment for said pressure medium from the empty bottle as it is being filled.

15. In an apparatus for transferring effervescent liquid from a full bottle to an empty bottle, means to hold a full bottle, and an empty bottle, including a sealing head, means movable relatively to said sealing head to establish communication between said bottles, a filter interconnected in said means of communication, pressure means to create and maintain constant pressure so as to cause the content of the full bottle to flow into the empty bottle, and refrigerating means to maintain the entire apparatus of a low temperature.

16. In an apparatus for transferring effervescent liquid from a closed bottle to another bottle, the combination with means to hold and to seal the mouth of the closed bottle, means to conduct a gas under pressure to said sealing means and a syphon element to convey liquid from the first to the second bottle, of a member on the inlet end of the syphon element adapted to penetrate through the closure of the full bottle, means to prevent the flow through said syphon element until the end of said piercing member reaches a predetermined position in the full bottle, said means to seal the mouth of the bottle conducting said gas under pressure into said bottle outside of the syphoning passage of said penetrating member.

17. In an apparatus for transferring effervescent liquid from one bottle to another, the combination with a holder for the full bottle and syphon means, of an intake member on said syphon means being adapted for insertion into the full bottle, means to prevent flow through said intake member, until the said intake member reaches a predetermined position in the full bottle, means to introduce a pressure medium to above the content of said full bottle through said sealing means.

18. In an apparatus for transferring effervescent liquid from a closed bottle to another bottle, the combination with means to hold and to seal the mouth of the closed bottle, and a syphon element to convey liquid from the first to the second bottle, of an intake member on the syphon element being movable through said sealing means, said member being adapted to open an aperture in the closure of the closed bottle larger than that portion of the intake member which is located in said aperture during the syphoning operation, and means to conduct gas under pressure to said aperture outside of said intake member.

19. In an apparatus for transferring effervescent liquid from a closed bottle to another bottle, the combination with means to hold and to seal the mouth of the closed bottle, and a syphon element to convey liquid from the first to the second bottle, of an intake member on the syphon element being movable through said sealing means, said member being adapted to open an aperture in the closure of the closed bottle larger than that portion of the intake member which is located in said aperture during the syphoning operation, and means to introduce a pressure medium into said full bottle through said sealing means and said aperture.

20. In an apparatus of the character described the combination with a closed full bottle held in operative relation to the intake end of syphoning means; of means on said intake end adapted to penetrate through the closure of the full bottle, means to render said syphoning means operative in a predetermined position of said penetrating means, and sealing means to conduct a pressure medium to the mouth of the bottle during the penetration and syphoning.

21. In an apparatus of the character described the combination with a closed full bottle held in operative relation to the intake end of syphoning means; of means on said intake end adapted to penetrate through the closure of the full bottle, means to automatically render said syphoning means operative in a predetermined position of said penetrating means, and sealing means to conduct a pressure medium to the mouth of the bottle during the penetration and syphoning.

WILLARD C. SAVILLE. 60
